(57) **CLAIM**

The ornamental design for a foam mitt, as shown and described.

DESCRIPTION

FIG. 1 is a front perspective view of a foam mitt of the present application;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

In the drawings, the broken lines depict environmental subject matter only and form no part of the claimed design.
